TRACK FOR TRACK-LAYING VEHICLES

Harry Ray Matheny, Highland Park, and Raymond Keefer, Detroit, Mich., assignors to Chrysler Corporation, Highland Park, Mich., a corporation of Delaware

Application October 9, 1942, Serial No. 461,384

11 Claims. (Cl. 305—10)

1

This invention relates to a track for track-laying vehicles and particularly to an improved track shoe for the same.

The principal object of our invention is to provide an all metal shoe which consists entirely of stamped parts.

Another object is to provide an improved metal track shoe having the grouser formed integrally therewith.

A further object is to provide a stamped track shoe which may be assembled from a minimum number of different stamped shapes.

A still further object resides in our improved means for retaining the stamped plates in assembled relation.

Other objects and advantages will be apparent from the following description which discloses preferred forms of the invention.

In the accompanying drawings,

Fig. 1 is a general view of a track-laying vehicle of the military type which incorporates our improved track.

Fig. 2 is a perspective view of our improved track shoe.

Fig. 3 is a section along line 3—3 of Fig. 2.

Fig. 4 is a section along line 4—4 of Fig. 2.

Fig. 5 is a perspective view of one of the stamped plates from which the shoe is assembled.

Fig. 6 is a view similar to Fig. 5 of a modified type of stamping.

Fig. 7 is a fragmentary perspective view of a shoe illustrating one method of fastening the plates together.

Fig. 8 is a detail perspective of the shoe, parts being broken away to show constructional details common to all of the different forms.

Fig. 9 is a fragmentary section of a shoe showing another method of fastening the plates.

Referring to the drawing it may be seen that our improved shoe, which is generally designated by reference numeral 10, is made up of a plurality of plates 11. In the particular example illustrated 48 plates are used, but this number may of course, vary in accordance with the weight of the vehicle.

The plates 11 may be of cast, rolled or stamped construction, but are preferably stamped from $\frac{1}{4}$ inch steel plate of suitable composition. Grouser tabs 12 are formed integrally on the plates 11 during stamping and, in order that the plates may be assembled to provide a grouser of the desired chevron shape, two different stamped shapes are provided. These two shapes are identical except for the location of the grouser tab 12, which in one case is disposed nearer the

2

center of the plate. Only two different positions of the tab 12 are required, the chevron shape of the grouser being obtained by reversing the position of one half of the plates to secure the necessary orientation. The preferred method of assembly of the plates is illustrated clearly in Fig. 2 from which showing it is obvious how the plates are assembled relatively to one another to secure the desired relationship of tabs.

10 The plates 11 are provided with holes 14 for receiving the link pins 16, and an opening 15 which serves to lighten the structure. The link pins 16 protrude a substantial distance beyond each end of the shoe for fastening to the shackle members 17 which form the articulated connecting means between adjacent shoes.

In assembling the shoe, the plates 11 are first assembled in proper relation and a split tube of thin wall section is inserted in each of the holes 14 of the assembled plates. These tubes, designated 19, are best shown in Figs. 4 and 8. After insertion they are peened over at each end (Fig. 4) to thereby retain the plates in assembly. The holes of the end plates are preferably ground 25 slightly bell-shaped to facilitate the engagement of the end portions of the tubes and to secure a tight lock.

The link pins 16 have rubber bushings 18 molded thereon. These bushings in their uncom- 30 pressed state are of considerably greater diameter than the interior of the tubes 19 and are spaced from one another on the link pins. By the use of a suitable insertion fixture the link pins are inserted into the tubes 19, the bush- 35 ings 18 being compressed under relatively great pressure such that the rubber flows axially of the pins to completely fill the space between the respective pins and the tubes.

The compression of the rubber bushings 18 40 subjects the relatively thin walled tube 19 to high radial pressure which results in the tube being deformed to conform to the irregularities of the hole caused by the roughness and slight non- 45 registering relation of the holes 14 of the stampings. This results in the tubes 19 gripping each individual plate as shown in Fig. 4 and a tightly locked assembly results.

Experimental tests under severe conditions 50 have demonstrated that no other means for holding the plates in assembled relation is necessary. As a matter of fact, when the shoes are used in service, "working" of the plates, pins and bushings causes the tubes 19 to deform to a greater extent and the shoe becomes to all 55 intents and purposes a solid structure.

In instances where rubber bushings under less pressure are used, or metal or plastic bushings are used some other means for retaining the plates in assembled relation is necessary.

Figs. 6 and 9 illustrate a form of the invention wherein each of the plates 11 is subjected to a coining operation for forming an indentation around one side of each of the holes 14 and an extrusion around the opposite side thereof. These indentations 20 and extrusions 21 (Fig. 6) cooperate upon assembly to form an interlock as clearly shown in Fig. 9.

Another method, illustrated in Fig. 7, consists in providing recesses 22 in each of the plates 11 at the time of stamping, and after assembly welding a reinforcing and retaining element 23 in each of the grooves formed by the aligned recesses.

Still another method comprises copper plating every other stamping and placing the assembled shoe in a hydrogen brazing furnace whereupon the individual plates are copper-hydrogen brazed to one another.

The interlocking construction, the welded beads 23 or the copper-hydrogen braze may be used individually or they may be combined if an exceptionally strong shoe is required. Any of these features either singly or in combination may be used with the friction lock means illustrated. It has, however, been experimentally determined that the friction lock shoe which depends solely on the adhesion between the tubes 19 and the rough surface of the holes 14 are satisfactory for all expected loads, and this shoe is more economical and easier to construct than those requiring additional machine or furnace operations.

Although but several specific embodiments of the invention are herein shown and described, it will be understood that various changes in the sequence of operations, steps and materials employed may be made without departing from the spirit of the invention.

We claim:

1. In a track for track-laying vehicles, a track shoe comprising a plurality of plates assembled in face-to-face relation, each of the plates being provided with openings adapted to register with similar openings in adjacent plates, a lock pin disposed in each set of openings, each of said openings having an extruded lip adapted to engage the opening in an adjacent plate thereby to prevent movement between plates.

2. In a laminated track shoe, means for securing the laminations together comprising an opening extending through the laminations; a thin walled tube in said opening, said tube being peened over at each end thereof around the ends of the opening; a link pin disposed in said tube having a rubber bushing fixed thereon and retained in radial compression by said tube, the radial compressive force thereof being sufficient to deform said tube and force it into intimate engagement with the interior of said opening.

3. The method of fabricating a track shoe which comprises stamping from sheet stock a plurality of laminations having openings therein adapted to register upon assembly of the laminations to provide an elongated hole through the shoe, forming on the respective laminations during stamping a projecting tab; assembling the laminations in predetermined pattern to provide a substantially flat upper track surface and an irregular lower track surface; inserting a relatively thin walled tube in said opening, and inserting in said tube a link pin and a mass of

rubber surrounding the link pin, the mass having before insertion an outer diameter greater than that of the inner diameter of the tube and thereby being compressed after insertion so as to force the tube into intimate engagement with the hole in the laminations.

4. The method of fabricating a track shoe which comprises stamping from sheet stock a plurality of laminations having openings therein adapted to register upon assembly of the laminations to provide an elongated hole through the shoe, forming on the respective laminations during stamping a projecting tab, forming a lip around each of said openings, assembling the laminations in predetermined pattern such that the respective lips interlock with the adjacent openings and the tabs form an irregular lower track surface, and securing the laminations together.

5. A track shoe comprising a plurality of laminations having an integrally formed tab at one edge thereof, said laminations being assembled with the tabs protruding outwardly from the body of the shoe to form a grouser, certain of said tabs being offset with respect to the other tabs to impart a definite tread pattern for the grouser, each lamination being formed with a projecting lip on one side and a recess on the other side, the projecting lip of one lamination engaging the recess in an adjacent lamination to prevent movement of the laminations with respect to one another.

6. In a track for track-laying vehicles, a track shoe comprising a plurality of plates assembled in face-to-face relation, each of the plates being provided with openings adapted to register with similar openings in adjacent plates, a lock pin disposed in each set of openings, each of said openings having at one side of a plate a projecting lip and at the other side a depression, the projecting lips engaging the depressions to prevent relative movement between the plates.

7. In a track for track-laying vehicles, a track shoe comprising a plurality of plates assembled in face-to-face relation, each of the plates being provided with openings adapted to register with similar openings in adjacent plates, a lock pin disposed in each set of openings, each of said openings having at one side of a plate a projecting lip and at the other side a depression, the projecting lips engaging the depressions to prevent relative movement between the plates, the plates being brazed to one another also to prevent relative movement.

8. A track shoe comprising a plurality of laminations having an integrally formed tab at one edge thereof, said laminations being assembled with the tabs protruding outwardly from the body of the shoe to form a grouser, certain of said tabs being offset with respect to the other tabs to impart a definite tread pattern for the grouser, the edge of each lamination opposite the tab being formed with recesses, the recesses of the laminations being aligned on assembly of the laminations to form grooves, and reinforcing and retaining elements laid in the grooves and metallically bonded to the laminations.

9. In a track for track-laying vehicles, a track shoe comprising a plurality of plates assembled in face-to-face relation, each of the plates being provided with openings adapted to register with similar openings in adjacent plates, a lock pin disposed in each set of openings, each of said openings having at one side of a plate a projecting lip and at the other side a depression, the projecting lips engaging the depressions to prevent relative movement between the plates, the plates

being brazed to one another also to prevent relative movement, the edge of each plate opposite the tab being formed with recesses, the recesses of the laminations being aligned on assembly of the plates to form grooves, and reinforcing and retaining elements laid in the grooves and metallically bonded to the plates.

10. A method of making a track shoe, comprising forming in each of a plurality of laminations having a projecting tab at one edge and an opening, a recess at one side of the lamination about the opening and a projecting lip at the other side about the opening by applying pressure about the opening at the said one side of the lamination, assembling the laminations so as to cause the projecting lips of the laminations to interlock with the recesses of the adjacent laminations and the tabs to form an irregular track surface, and securing the laminations together.

11. A track shoe comprising a stack of laminations having aligned openings, a thin wall tube positioned in said openings, a link pin positioned

in the tube, and a rubber bushing positioned between said tube and said pin and being under radial compressive force sufficient to deform the tube into intimate engagement with the aligned openings in the stack of laminations.
